UNITED STATES PATENT OFFICE

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY

FASTENING INSERTING MACHINE

Application filed February 12, 1929, Serial No. 339,409, and in Great Britain August 1, 1928.

This invention relates to fastening inserting machines and is illustrated herein as embodied in a machine arranged to sever fiber pegs from a strip of fiber material and to insert the pegs in the sole portions of shoes.

When inserting fiber pegs to secure together parts of shoe bottoms it is often desirable that the lengths of the pegs be varied in accordance with the thickness of the different portions of the shoe bottoms into which they are driven. This gives the pegs maximum holding power and insures that they will not pull out even from thin insoles. The heel seats of, for example, Goodyear welt shoes are nailed or pegged on the last and, accordingly, it is impossible to caliper the thickness of the shoe bottom as might be done if the operation were performed off the last. It is practicable, however, as illustrated in an application of Letters Patent of the United States, Serial No. 314,468, filed October 23, 1928, in the name of Fred C. Eastman, to utilize the awl of a fastening inserting machine to measure the thickness of shoe bottoms, the awl coming to rest when it meets excessive resistance, as when it strikes an impenetrable member back of the shoe bottom, such as the metal heel plate or bottom plate of a last.

It is an object of the invention to provide improved means applicable, for example, to machines of the type used for heel seat nailing, by which the awl may be permitted to come to rest without injury to the machine when the awl meets excessive resistance, for example when it has passed through a shoe bottom and strikes the iron heel-plate of a last on which the shoe is mounted.

It is another object of the invention to provide a machine for inserting fastenings in the bottom of a shoe mounted on a last arranged to measure the thickness of the shoe bottom, to feed the shoe to and past the fastening inserting instrumentalities, and to insert in the shoe bottom fastenings each of a length corresponding to the measured thickness of the shoe bottom at the point where it is inserted.

It is a further object of the invention to provide improved means for supplying to the

fastening instrumentalities of a fastening inserting machine fastenings such as fiber pegs each of a length determined by the thickness of the work piece at the point where it is to be inserted.

In accordance with the foregoing, a feature of the invention comprises awl reciprocating mechanism including yielding means, illustrated as a stiff compression spring, serving to transmit work penetrating movement to the awl and arranged to yield and permit the awl to come to rest when the awl meets an excessive resistance in its work penetrating movement.

In accordance with another feature of the invention the illustrated machine is provided with improved means for feeding a strip of fiber fastening material to and past fastening severing means, the length of each feeding movement of the fastening material being controlled by the depth to which the awl of the machine has penetrated the work piece in forming a hole for the reception of the fastening which is about to be severed.

While the invention is illustrated herein as embodied in a fastening inserting machine particularly adapted to drive fiber pegs into the sole portions of shoes, for example in heel seat pegging, it should be noted that the invention is not limited in its utility to such use or to embodiment in fastening inserting machines of the type illustrated and, accordingly, the construction disclosed herein should be regarded as merely one example of the forms in which my invention may be embodied.

With the above and other objects in view the invention will now be described with reference to the accompanying drawings and pointed out in the claims.

In the drawings,

Fig. 1 is a side elevation of the head of a fastening inserting machine embodying my invention;

Fig. 2 is a front elevation of the head of the machine of Fig. 1;

Fig. 3 is a longitudinal section of a spring connection shown in Figs. 1 and 2 and serving to transmit reciprocating movement to the awl of the machine;

Fig. 4 is a sectional view on the line IV—IV of Fig. 1;

Fig. 5 is a side elevation of the machine looking in the opposite direction to Fig. 1 and showing a cross section of a shoe upon a last and presented to the machine, as for the performance of the heel seat nailing or pegging operation; and

Fig. 6 is a diagrammatic view showing how fiber severed from the material of the shoe bottom serves to cushion the end surface of the awl as the latter strikes the metal bottom plate of a last in the heel seat pegging operation.

The illustrated machine is of the general type disclosed in Letters Patent of the United States No. 1,030,775, granted June 25, 1912, on an application filed in the name of George Goddu, though organized to insert fiber pegs severed from a strip of fastening material such as paper twine instead of loose nails. The machine may be advantageously equipped with a work support of the character disclosed in Letters Patent of the United States No. 1,587,848, granted June 8, 1926, on an application filed in the name of F. L. MacKenzie, the pressure relieving mechanism being modified, if desired, as shown in Figs. 23 and 24 of Letters Patent of the United States No. 1,686,808, granted October 9, 1928, on an application filed in the names of George Goddu and F. L. MacKenzie. Reference may be had to these patents for a full disclosure of such parts of the machine as it is unnecessary to illustrate herein.

The illustrated machine is provided with a column 10 carrying a head 12 on which are mounted the fastening inserting instrumentalities of the machine. The column 10 also carries a work support terminating in a last pin 14 (Fig. 5) arranged to support a work piece such as a shoe 16 mounted upon a last 18 with its sole 20 in engagement with a presser plate or abutment 22 carried by the head 12 of the machine. The shoe may be positioned relatively to the fastening inserting instrumentalities of the machine by a gage 24, which may take any suitable form, also carried by the head 12 of the machine.

Mounted in suitable bearings carried by the head of the machine is a cam shaft 30 carrying a cam member 32 provided with a series of cam grooves and surfaces arranged to operate the moving parts of the machine. Loose upon the cam shaft 32 near the rear end thereof is a pulley 36 driven from any suitable source of power by a belt 37. Slidably mounted on the shaft 30 is a clutch member 38 having a clutch surface 40 arranged for movement into and out of driving relation with a clutch surface 42 formed on the pulley 36. The clutch member 38 is also provided with a brake surface 44 arranged for movement into and out of braking relation with a brake surface 46 carried by the head 12 of the ma-

chine. A spring 50 surrounding the shaft 30 tends to move the clutch member 38 into driving relation with the pulley 36, but permits the clutch member 38 to be moved away from the pulley 36 and into engagement with the brake surface 46 by power transmitted from a cam surface 52, with which the cam member 32 is provided, when the treadle rod 54 is depressed by a spring 55 upon the releasing of a treadle connected to the lower end of the rod 54. For a fuller disclosure of this mechanism, which forms no part of the present invention, reference may be had to Letters Patent of the United States No. 1,030,775 referred to above.

The machine is provided with a driver bar 60 mounted for reciprocating movement in vertical ways carried by the head 12 of the machine adjacent to the forward end of the shaft 30. Clamped to the lower end of the driver bar 60 is a driver 62. The driver bar 60 is provided with a rack 64 meshing with a gear segment 66 formed upon the end of the forwardly extending arm of a bell crank lever 68 fulcrumed at 70 to the head 12 of the machine and having a depending arm carrying at its lower end a roll positioned in a cam track 72 formed in the cam member 32.

An awl bar carrier 80 (best shown in Fig. 2) is mounted for horizontal sliding movement at the front of the machine and mounted for vertical sliding movement in ways formed in the awl bar carrier 80 is an awl bar 82 carrying at its lower end an awl 84. The rear surface of the awl bar 82 is provided with a rack 86 meshing with a gear segment 88 formed upon the forward end of a lever 90 fulcrumed at 92 to the head 12 of the machine and provided with a pair of rearwardly extending arms 94 and 96 (Fig. 1). The awl bar carrier 80 is reciprocated transversely of the machine by a lever 100 fulcrumed to the head 12 of the machine and carrying a roll positioned in a cam groove formed in the rear surface of a cam disk 102 secured to the forward end of the shaft 30. The arm 96 of the lever 90 is yieldingly and adjustably connected to a bell crank lever 104 (Fig. 1) fulcrumed at 106 to the head 12 of the machine and carrying a cam roll positioned in a cam track 108 formed in the cam member 32. Thus the awl 84 serves both to form fastening receiving holes in a work piece presented thereto and to feed the work piece toward and past the driver 62, constituting a four-motion feed.

In order to permit the awl 84 to come to rest when it hits the metal bottom plate 110 (Figs. 5 and 6) of the last 18, the connection between the arm 96 of the lever 90 and the bell crank lever 104 includes a bodily moving spring 112 (see particularly Figs. 1 and 3) stiff enough to transmit sufficient power to the awl 84 to drive the awl into and through the material of a shoe bottom with-

out substantially but sufficiently yielding so that it is compressed and permits the awl to come to rest when it strikes the metal bottom plate 110 even though the bell crank lever 104 has not finished its rocking movement. Thus it will be seen that the extent of the downward movement of the awl 84 beneath the lower surface of the presser plate 22 serves to measure the thickness of the layers 10 of the bottom of the shoe mounted upon the last 18.

The spring 112 surrounds a sleeve 114 (Fig. 3) pivoted at its lower end to the arm 96 of the lever 90 and carrying at its upper end a nut 116 which serves as an abutment for the upper end of the spring 112. The lower end of the spring 112 abuts against a collar 118 slidably mounted on the sleeve 114 and carried at the lower end of a pair of parallel bars 120 pivoted at their upper ends to a short sleeve 122 (Fig. 4) carried by a stud 124 adjustably mounted in a slide-way 126 formed in the forwardly extended arm of the bell crank lever 104. A nut 128 is threaded upon the outer end of the stud 124 and engages a washer 130 bearing against the outer surface of the upper end of the parallel bar member 120. The stud 124 is thus adjustably secured to the bell crank lever 104 which may be provided with a scale 132 (Fig. 1) to indicate the depth of the fastening receiving holes formed by the full stroke of the awl at the various positions of adjustment of the stud 124. Clamped to the nut 116 is a bearing member 134 engaging machined surfaces 136 formed upon the parallel bars 120 and serving to prevent relative displacement (other than lengthwise) of the members 114 and 120.

40 The fiber fastening material 140 from which the pegs inserted by the machine are severed is carried by a reel 142 mounted upon a bracket 144 secured to the head 12 of the machine. The strip 140 of fiber fastening material is engaged by a feed dog 146 (Fig. 2) of the feeding mechanism, which will presently be described, and by a spring pressed holding dog 148 designed to prevent retrograde movement of the fastening material, after which it enters a passage-way 150 the lower end of which is in alinement with the driver passage of a forwardly and rearwardly reciprocating throat member 152 when the latter is in its rear-most position. 55 Forward movement of the throat member 152 thus serves to sever a peg from the fastening material 140 and the length of this peg, as hereinafter described, is determined by the awl stroke, that is by the distance which the awl has penetrated the work piece before being brought to rest by striking the metal heel plate 110 of the last. The throat member 152 is carried by the forward end of a bar 154 (Fig. 5) mounted for forward and rearward movement in ways carried by the head

12 of the machine and provided near its rear end with a rack 156 engaging a gear segment 158 formed at the lower end of a lever 160 fulcrumed at 162 to the head 12 of the machine and provided with a roll positioned in a cam track 164 formed in the cam member 32.

The feed dog 146 (Fig. 2) is pivoted to the end of a pair of parallel links 170 pivoted at 172 to a pair of ears depending from a block 174 formed at the lower end of a tubular member 176 which forms a guide for the fastening material 140 and is mounted for reciprocating movement lengthwise of the strip of fastening material 140 in a slide-way formed in a bracket 178 secured to the head 12 of the machine. The extent of the reciprocation of the block 174 will, of course, determine the length of fastening material fed. Accordingly, the machine is so organized that the reciprocation of the block 174 is controlled by the awl bar 82 and bears a definite relation to the distance which the awl is projected below the presser plate 22 of the machine in each cycle of operation.

Accordingly, the block 174 is pivoted to a block 179 mounted in slideways formed at the forward end of a lever 180 fulcrumed at 182 to the head 12 of the machine and having a rearwardly and upwardly extending arm pivoted at 184 to the forward end of a link 186. The link 186 is pivoted intermediate between its ends to the forward end of another link 188, the rear end of which is adjustably pivoted by a bolt and slot connection 190 to a lever 192 fulcrumed at 194 to the head 12 of the machine and provided with a rearwardly extending arm carrying a roll positioned in a cam track 196. As illustrated the lever 192 is effective also to transmit the pressure relieving movement to the work support 14 which facilitates the feeding of the work, that movement being transmitted through a rod 198 to mechanism of the character disclosed in Letters Patent of the United States No. 1,587,848, modified if desired as shown in Figs. 23 and 24 of Letters Patent of the United States No. 1,686,808.

At its rear end the link 186 is provided with a slide member positioned in an arcuate slot 200 formed in the upwardly and rearwardly extending end of a lever 202 fulcrumed at 204 to the head 12 of the machine and having a forwardly extending arm provided with a gear segment 206 meshing with a gear segment 208 formed upon the arm 94 of the lever 90. Thus it will be seen that the lever 202 will be rocked through an angle which is determined by the extent of the reciprocation of the awl bar 82. The slot 200 has a radius of curvature equal to the effective length of the link 186, and the lever 202 is so positioned that the slot 200 is concentric with the pivot 184 between the lever 180 and the link 186 when the parts are in the position

125

130

which they occupy when the entering end of the awl 84 is flush with the lower surface of the presser plate 22. As the awl 84 descends below this position the lever 202 is rocked in 5 a counter-clockwise direction, as viewed in Fig. 5, the extent of this rocking movement depending upon the distance which the awl moves before it is stopped by impact with the metal plate 110 of the last 18. Thus the 10 rocking movement of the lever 192, which is uniform in each cycle of operation of the machine, is varied as it is transmitted to the lever 180, the extent of the rocking movement of the lever 180 increasing with the increased 15 eccentricity of the slot 200 relatively to the pivot 184 caused by an increased work penetrating movement of the awl 84.

The bolt and slot adjustment 190 between the lever 192 and the link 188 permits the 20 length of the fastening material fed to be increased a greater or lesser amount over the thickness of the work piece penetrated by the awl 84 so as to allow for the heading of the fastening which takes place if the fastening is somewhat longer than the thickness of the work piece in which it is inserted.

In the operation of the machine the last 18 upon which the shoe 16 is mounted is placed 25 on the last pin 14 of the work support, the shoe being positioned by the gage 24 in the manner usual in performing the heel seat nailing operation. When the machine is started the awl 84 is thrust downwardly into the sole until its lower end comes substantially into contact with the metal bottom plate 110 of the last, being cushioned, however, by a small amount of leather fiber (as shown at 210 in Fig. 6) severed by the awl 30 as it passes through the outsole and the other layers of the shoe bottom. Preferably, in order to augment this cushion effect, the awl is cylindrical in form and is provided with a plane entering end formed at right angles 35 to the longitudinal axis of the awl. When the awl strikes the metal bottom plate 110 of the last, the spring 112 is compressed so that the bell crank lever 104 is enabled to complete its rocking movement in a clockwise direction, as viewed in Fig. 1. The awl is 40 then moved transversely to the left, as viewed in Fig. 2, feeding the work piece and bringing the awl into the line of drive. The awl is then withdrawn and returned to the 45 position which it occupied at the beginning of the cycle of operation. The work piercing or penetrating movement of the awl which has just been described is effective, through the connection between the awl bar 82 and the lever 202, to rock the lever 202 in a counter-clockwise direction, as viewed in Fig. 5, to a 50 position which is determined by the thickness of the shoe bottom as measured by movement of the awl, thus controlling the angular relation between the link 186 on the one hand

and the lever 202 and the link 188 on the other, so that the rocking movement of the lever 90 rocks the lever 180 to an extent sufficient to cause the latter to move the block 174 through a path which causes the feed dog 146 and a surface formed on the block 174 with which the feed dog 146 cooperates to move through a path sufficient to feed the fastening material a distance equal to or, if desired, slightly more than the thickness of the shoe bottom parts which the awl 84 penetrates. The fastening material is then severed by the forward movement of the throat member 152 and is brought forward into line with the driver 62 which descends to 70 drive the fastening into the hole formed by the awl 84 in the shoe bottom.

Having thus described my invention what I claim as new and desire to secure by Letters Patent of the United States is:

1. A fastening inserting machine having, in combination, means for measuring the thickness of the bottom of a shoe mounted on a last, means for inserting in the bottom of the shoe fastenings of a length corresponding to the measured thickness of the shoe bottom, and means for feeding the shoe to and past the fastening inserting means between the insertion of successive fastenings.

2. In a fastening inserting machine, the combination of an awl carrier, an awl carried thereby, and means for reciprocating the awl carrier thereby thrusting the awl into a work piece presented thereto and including a spring serving to transmit reciprocating motion to the awl carrier, said spring being substantially unyielding during the work penetrating movement of the awl but arranged to yield when the awl meets an excessive resistance.

3. In a fastening inserting machine, the combination of an awl, means for operating the awl to form fastening receiving holes in a work piece presented thereto including a spring substantially unyielding during the work penetrating movement of the awl but arranged to yield when the awl meets an excessive resistance in its work-penetrating movement, and means for operating the awl to feed the work piece.

4. In a fastening inserting machine, the combination of an awl, means for operating the awl to form fastening receiving holes in a work piece presented thereto including a spring bodily movable to transmit work-penetrating movement to the awl and arranged to yield when the awl meets an excessive resistance in its work-penetrating movement, a driver, and means for operating the driver to drive fastenings into the holes formed by the awl.

5. In a fastening inserting machine, the combination of an awl carrier, an awl carried thereby, means for reciprocating the awl carrier including a spring bodily movable to

transmit reciprocating motion to the awl carrier and arranged to yield when the awl meets an excessive resistance, a driver, means for operating the driver to insert fastenings in the holes formed by the awl, and means for presenting to the driver fastenings of a length corresponding to the depth of the respective holes formed by the awl.

6. In a fastening inserting machine, the combination of an awl, means for operating the awl to form fastening receiving holes in a work piece presented thereto including a connection substantially unyielding during the work-penetrating movement of the awl but constructed and arranged to yield when the awl meets an excessive resistance in its work-penetrating movement, and means for operating the awl to feed the work piece.

7. In a fastening inserting machine, the combination of an awl, means for operating the awl to form fastening receiving holes in a work piece presented thereto including a spring moved bodily to transmit work-penetrating movement to the awl and arranged to yield when the awl meets an excessive resistance in its work-penetrating movement, and means for operating the awl to feed the work piece.

8. A fastening inserting machine having, in combination, an awl carrier, an awl carried thereby, means for causing the awl to penetrate a work piece including a spring movable bodily and without expansion to transmit work-penetrating movement to the awl and arranged to yield when the awl meets an excessive resistance, a driver, and means for operating the driver to insert fastenings in the holes formed in the work piece by the awl.

9. A fastening inserting machine having, in combination, an awl, a driver, means for causing the awl to penetrate the bottom of a shoe mounted on a last constructed and arranged to permit the awl to be arrested by the metal bottom plate of the last, means for moving the awl transversely of the direction of its work penetrating movement thereby feeding the work to bring the hole formed by the awl into alignment with the driver, and means for operating the driver to insert in the hole formed by the awl a fastening of a length corresponding to the thickness of the shoe bottom.

10. A fastening inserting machine having, in combination, fastening inserting instrumentalities including an awl, means for reciprocating the awl to form fastening receiving holes in a work piece, means for inserting in the hole formed by the awl fastenings the lengths of which are determined by the length of the path of movement of the awl when forming the holes in which the respective fastenings are to be inserted and means for moving the awl transversely of the

direction of its reciprocating movement to feed the work piece between the insertion of successive fastenings.

11. A fastening inserting machine having, in combination, cyclically operating means for severing pegs from a strip of paper peg material and inserting the pegs in a work piece, and means for feeding the work piece between the insertion of successive pegs constructed and arranged also to control the lengths of the different pegs severed from the peg material in accordance with the thickness of the work piece at the points where the respective pegs are to be inserted.

12. A fastening inserting machine having, in combination, cyclically operating means for inserting a series of fastenings in a work piece, means for feeding the work piece between the insertion of successive fastenings including an awl arranged to measure the thickness of the work piece at the point where each fastening is to be inserted, and means for presenting to the fastening inserting means fastenings each of a length corresponding to the measured thickness of the work piece at the point where the fastening is to be inserted.

13. A fastening inserting machine having, in combination, an awl, means for reciprocating the awl to form fastening receiving holes in a work piece presented thereto including a spring serving to transmit work penetrating movement to the awl and arranged to yield when the awl meets an excessive resistance thereby permitting the awl to come to rest, means for severing from a strip of fastening material fastenings of a length corresponding to the depth to which the awl penetrates the work piece in forming holes for the respective fastenings, and a driver arranged to insert the fastenings in the holes.

14. In a fastening inserting machine, the combination of an awl, means for operating the awl to form fastening receiving holes in a work piece presented thereto including a spring serving to transmit work penetrating movement to the awl and arranged to yield when the awl meets an excessive resistance in its work penetrating movement, means for severing fastenings from a strip of fastening material, and means for feeding the strip of fastening material past the severing means constructed and arranged to cause the material fed past the severing means, which material is to be severed from the strip to serve as a fastening, to correspond in length to the thickness of the material penetrated by the awl when forming the hole for that fastening.

15. A fastening inserting machine having, in combination, an awl, mechanism for reciprocating the awl to cause the awl to form fastening receiving holes in a work piece presented thereto and including a spring serving to transmit the reciprocating movement to the awl and arranged to yield when

- the awl meets an impenetrable member back of the work piece, whereby the length of the awl stroke is dependent upon the thickness of the work piece, means for severing fastenings from a strip of fastening material, means for feeding the strip of fastening material past the severing means arranged to cause the length of material fed prior to the severing of each fastening to correspond to the thickness of the material through which the awl has penetrated in forming the hole for that fastening, and a driver arranged to insert fastenings in the holes formed by the awl in the work piece.
- 15 16. A fastening inserting machine having, in combination, a driver, means for reciprocating the driver to insert fastenings in a work piece presented thereto, an awl, means for causing the awl to penetrate the work to a depth determined by the thickness of the work and to feed the work to bring the hole formed by the awl into alignment with the driver and then to withdraw from the work, and means for presenting for insertion by 20 the driver fastenings of a length determined by the depth to which the awl has penetrated the work in forming the holes for the respective fastenings.
- 25 17. A fastening inserting machine having, in combination, a driver, means for reciprocating the driver to insert fastenings in a work piece presented thereto, an awl, means for causing the awl to penetrate the work to a depth determined by the thickness of the work and to feed the work to bring the hole formed by the awl into alignment with the driver and then to withdraw from the work, and means constructed and arranged to sever from a strip of fastening material a fastening 30 of a length determined by the depth to which the awl has penetrated the work and to present the fastening for insertion by the driver in the hole.
- 35 18. A fastening inserting machine having, in combination, means for piercing a work piece into which a fastening is to be inserted, thereby measuring the thickness of the work piece, means for severing fastenings from a strip of fastening material, means for feeding the strip of fastening material to the severing means including a lever the extent of 40 the rocking of which determines the length of the feeding movement imparted to the strip and hence determines the length of the 45 fastenings severed, and means for rocking said lever to an extent determined by the thickness of the work piece as measured by said piercing means.
- 50 19. A fastening inserting machine having, in combination, an awl arranged to penetrate a work piece and to be stopped by an impenetrable member back of the work piece, means for severing fastenings from a strip of fastening material, and means for feeding the 55 strip of fastening material to the severing

means including a lever the extent of the rocking of which determines the length of the feeding movement imparted to the strip and hence determines the length of the fastenings severed, and means for rocking said lever through a path, the extent of which is determined by the thickness of the work piece penetrated by the awl.

20. A fastening inserting machine having, in combination, an awl and means for reciprocating the awl to form fastening receiving holes in a work piece presented thereto comprising a lever, means for rocking said lever, a second lever arranged by its rocking movement to reciprocate the awl, and a spring 75 connecting the two levers arranged to permit the first lever to continue its rocking movement when the second lever is no longer able to rock by reason of the awl having met an excessive resistance in its work-penetrating movement.

21. A fastening inserting machine having, in combination, an awl and means for reciprocating the awl to form fastening receiving holes in a work piece presented thereto comprising a cam, a lever rocked by the cam, a second lever arranged by its rocking movement to reciprocate the awl, and a spring connecting the two levers arranged to transmit rocking movement from the first lever to the second lever and to permit the first lever to continue its rocking movement when the second lever is no longer able to rock by reason of the awl having met an impenetrable member by which the work piece is backed up.

22. A fastening inserting machine having, in combination, an awl, means for reciprocating the awl through a path the length of which is determined by the thickness of the work piece into which the awl is inserted, a rack arranged to reciprocate with the awl, a lever having a gear sector engaging with said rack and thus rocked through an angle the extent of which is determined by the thickness of the work piece into which the awl is inserted, and means controlled by said lever for severing from a strip of fastening material fastenings of a length corresponding to the thickness of the work piece at the points where the respective fastenings are to be inserted.

23. A fastening inserting machine having, in combination an awl bar, an awl carried thereby, means for reciprocating the awl through a path the length of which is determined by the thickness of the work piece into which the awl is inserted, a rack formed on the awl bar, a lever having a gear sector engaging with said rack and thus rocked through an angle the extent of which is determined by the thickness of the work piece into which the awl is inserted, and means controlled by said lever for severing from a strip of fastening material fastenings of a

length corresponding to the thickness of the work piece at the points where the respective fastenings are to be inserted.

24. A fastening inserting machine having, in combination, an awl, an awl bar by which the awl is carried, a lever arranged by its rocking movement to reciprocate the awl bar, another lever, a cam arranged to rock said last-named lever, and a spring connecting the two levers constructed and arranged to permit the last-named lever to complete its normal rocking movement even though the first-named lever is prevented from rocking by reason of the engagement of the awl with an impenetrable member.

25. A fastening inserting machine having, in combination, an awl, an awl bar by which the awl is carried, a lever arranged by its rocking movement to reciprocate the awl bar thereby causing the awl to penetrate a work-piece presented thereto, means for moving the awl transversely of its work-penetrating movement to cause the awl to feed the work piece, another lever, a closed cam arranged positively to rock said last-named lever, and a compression spring connecting the two levers constructed and arranged to permit the last-named lever to complete its normal rocking movement even though the first-named lever is prevented from rocking by reason of the engagement of the awl with an impenetrable member.

26. A fastening inserting machine having, in combination, means operative in each cycle of operation of the machine for measuring the thickness of a work piece into which fastenings are to be inserted, a controlling lever rocked by said measuring means through an angle in each cycle of operation the extent of which is determined by the measured thickness of the work piece, a lever rocked through a uniform angle in each cycle of operation of the machine, means for engaging a strip of fastening material and operable to feed the fastening material, a feed lever connected to said means the extent of the rocking movement of which determines the length of fastening material fed, and connections between the three levers constructed and arranged to cause the uniformly rocked lever to transmit to the feed lever rocking movement the extent of which is determined by the position to which the controlling lever is rocked.

27. A fastening inserting machine having, in combination, means for measuring the thickness of a work piece, a driver arranged to insert fastenings in the work piece, and means for presenting fastenings to the driver including mechanism arranged to control the length of the various fastenings in accordance with the measured thickness of the work piece at the point where the respective fastenings are to be inserted, said mechanism comprising a lever the extent of the rocking

movement of which in each cycle of operation of the machine determines the length of the fastening inserted in that cycle, a second lever rocked through a constant angle in each cycle of operation, and variable connections between the two levers constructed and arranged to cause the constantly rocked lever to rock the other lever through an angle the extent of which in each cycle of operation is determined by the measured thickness of the work piece at the point where a fastening is to be inserted in that cycle of operation.

28. A fastening inserting machine having, in combination, an awl arranged to penetrate a work piece and to be stopped by striking an impenetrable member back of the work piece, a controlling lever, connections between the awl and said lever constructed and arranged to rock said lever through an angle the extent of which is determined by the thickness of the work piece at the point where it is penetrated by the awl, a lever rocked through a uniform angle in each cycle of operation of the machine, means for engaging a strip of fastening material and operable to feed the fastening material, a feed lever connected to said means the extent of the rocking movement of which determines the length of fastening material fed, and connections between the three levers constructed and arranged to cause the uniformly rocked lever to transmit to the feed lever rocking movement the extent of which is determined by the position to which the controlling lever is rocked.

29. A fastening inserting machine having, in combination, an awl arranged to penetrate a work piece and to be stopped by an impenetrable member back of the work piece, a driver arranged to insert fastenings in the holes formed by the awl in the work piece, and means for presenting fastenings to the driver including mechanism arranged to control the length of the various fastenings in accordance with the measured thickness of the work piece at the point where the respective fastenings are to be inserted, said mechanism comprising a lever the extent of the rocking movement of which determines the length of a fastening, a second lever rocked through a constant angle in each cycle of operation of the machine, and variable connections between the two levers arranged to cause the constantly rocked lever to rock the other lever through an angle the extent of which is determined by the extent of the work piece penetrating movement of the awl.

In testimony whereof I have signed my name to this specification.

FRED N. LA CHAPELLE.
